UNITED STATES PATENT OFFICE

CHARLES S. FOSTER, OF PAWTUCKET, RHODE ISLAND, ASSIGNOR TO FALES & JENKS
MACHINE COMPANY, OF PAWTUCKET, RHODE ISLAND, A CORPORATION.

SPINDLE.

No. 886,789.

Specification of Letters Patent.

Patented May 5, 1908.

Application filed March 1, 1906. Serial No. 303,623.

To all whom it may concern:

Be it known that I, CHARLES S. FOSTER, a citizen of the United States, residing at Pawtucket, in the county of Providence and 5 State of Rhode Island, have invented certain new and useful Improvements in Spindles, of which the following is a specification.

My invention relates to new and useful improvements in spindles for spinning and 10 twisting cotton, etc., and more particularly to that class of spindles which have a knee brake, a knee brake post, and a friction finger, to extend over and be engaged by the whirl on the spindle to stop the rotation of the 15 spindle, when the spindle is raised by the operation of the knee brake.

The object of my invention is to improve upon the construction of the knee brake and the friction finger, as ordinarily made, and 20 particularly to provide a finger, to be engaged by the whirl on the spindle, which will have a rotary motion, and will be held or locked in its operative position.

My invention consists in certain novel features of construction of my improvements as 25 will be hereinafter fully described.

I have shown in the drawing a spindle of the class referred to, and a knee brake, and a knee brake post, and a friction finger embodying my improvements.

Referring to the drawing:—Figure 1 is a side view of a spindle, and of the other parts embodying my improvements. Fig. 2 is a central vertical section through the friction finger and the knee brake lever post or guide, and shows the locking spring. Fig. 3 is a 35 plan view of the friction finger shown in Fig. 1, looking in the direction of arrow *a*, same figure. Fig. 4 corresponds to Fig. 2, but shows the opposite position of the friction finger. Fig. 5 corresponds to Fig. 3, but shows the opposite position of the friction finger. Fig. 6 shows a modified construction of the upper side of the friction finger, and, Fig. 7 is a plan view of a part of the knee 45 brake lever, detached, looking in the direction of arrow *a*, Fig. 1.

In the accompanying drawing, 1 is the supporting case or bolster provided with the ordinary flange 1' thereon, to rest on the top 50 of the spindle rail, not shown, and having the external screw thread 1" for the binding nut, not shown.

The knee brake lever 3, so-termed, acts as 55 a brake lever for the spindle, and is loosely

supported on the upper side of the flange 1' of the supporting case or bolster 1, and has a central opening therethrough, see Fig. 7, through which the bolster loosely extends, as is customary. The knee brake lever 3 has 60 the downwardly extending part or engaging end 3', to be engaged by the knee of the operator, and a weighted end 3'', which acts to restore the knee brake lever 3 to its normal horizontal position, after the end 3' is released by the operator. There is an elongated opening 3''' in the knee brake, see Fig. 7, for the knee brake post, which extends loosely through said opening, and acts to hold the knee brake in position, and prevent 70 rotary movement thereof.

A leather washer 4 loosely encircles the bolster 1, and is supported upon the upper side of the knee brake lever 3, and extends between said knee brake lever and the lower 75 surface of the whirl 5 on the spindle 6, in the usual way as is customary.

In operating the knee brake lever 3, the operator moves inwardly, or towards the bolster 1, the downwardly extending end 80 3', causing the knee brake to be tilted on the flange 1', and the leather washer 4 thereon brought into engagement with the underside of the whirl 5 to act as a brake for said whirl, and to apply friction thereto, and at the same 85 time to raise the whirl 5, to cause the upper surface thereof to engage the friction finger, to be hereinafter described.

All of the above mentioned parts may be of the usual and well known construction. 90

I will now describe my improvements, which as above stated relate particularly to the knee brake lever, and the friction finger, which finger in its normal position extends over the whirl and is adapted to be engaged 95 thereby, through the movement of the knee brake, to stop the rotation of the spindle.

The friction finger 7 is preferably made with a sleeve or hub portion 7', which in this instance, at its lower end, fits loosely over 100 the knee brake post 8, which in this instance is made integral with the flange 1', and extends up therefrom upon the opposite side of the spindle from the oil receptacle 11.

The hub 7' is held on the post 8, to have a 105 rotary motion, by a screw 9, which is screwed into a threaded hole in the post 8, and held therein by a nut 10. The upper end of the screw 9 extends loosely through an opening in the upper end of the hub 7', and the head 110

9' of the screw 9 extends in a countersunk or recessed portion on the upper end of the hub 7', and has one side cut off, or provided with a straight edge, to engage a straight edge 7" on the upper end of the hub 7', as shown.

- 5 A helically coiled expansion spring 12 extends, in this instance within the hub 7' of the finger 7, and bears at one end against the upper end of the post 8 and at its other end 10 against the upper inner end of the hub 7', and acts to yieldingly hold the hub 7' in its raised position, and bearing against the head 9' of the screw 9, so that when the straight edge on the head 9' engages the straight surface 7" on the upper end of the hub 7', any 15 rotation of the hub will be prevented, and it will be locked and held with the finger 7 in operative position, extending over the whirl 5, as shown in Fig. 1.
- 20 The finger 7 has in this instance an opening therethrough in which is secured a piece of leather or other material 7", to engage the upper side of the whirl 5.

When it is desired to move the finger 7 out 25 of the path of the whirl 5, to remove the spindle, the hub 7' is pressed down slightly, against the action of the spring 12, sufficient to release the straight surface 7" thereon from the head 9' of the screw 9, and then the 30 hub 7' is rotated to carry the finger 7 away from the whirl, and to move it into an opposite position, as shown in Fig. 4.

The knee brake lever 3 has as above stated an opening 3"" therein through which loosely 35 extends the post 8 and also the hub 7' of the finger 7. The opening 3"" is preferably elongated, see Fig. 7 and made of sufficient length to allow of the finger 7 passing therethrough, when it is in its inoperative position, or in the position shown in Fig. 4, so 40 that the knee brake lever, after the spindle has been removed, may also be removed without removing the finger 7.

In Fig. 6 is shown a modified construction. 45 of the upper end of the hub 7'. In said figure, the screw head 9' is shown with two straight edges, adapted to engage two straight portions on the recessed part of the upper end of the hub 7'. By this construction of the head 9' of the screw 9, and of the upper end of the hub 7', the friction finger 7 is locked in its operative position, and also 50 in its inoperative position, as will be readily understood.

55 The operation of my improvements will be readily understood by those skilled in the art. In the normal operation of the spindle, in spinning and twisting cotton, etc., the knee brake lever 3 and friction finger 7 will be in 60 the position shown in Fig. 1 of the drawing. When it is desired to stop the spindle, the knee brake lever 3 is operated, as above described, by the operator, to raise the whirl 5 and spindle 6, and bring the upper surface 65 of the whirl into engagement with the friction

surface 7"" on the finger 7, to stop the rotation of said whirl and spindle.

In case it is desired to remove the spindle 6, the finger 7 is pressed downwardly, against the action of the spring 9, and the hub 7' 70 thereof given a half rotation, to carry the finger 7 from the position shown in Figs. 2 and 3, to the position shown in Figs. 4 and 5, thus leaving a free space for the removal of the spindle 6 and the whirl 5 thereon, and also 75 allowing of the removal of the knee brake lever 3, by reason of the opening 3"" therein, all as will be understood by those skilled in the art.

The advantages of my improvements will 80 be readily appreciated by those skilled in the art. The friction finger 7 will be held or locked in its operative position, and may be readily moved out of the path of the whirl on the spindle so that the spindle may be readily 85 removed.

It will be understood that the details of construction of my improvements may be varied if desired.

The movable friction finger 7 may be used 90 in place of the ordinary retaining hook, to extend over the whirl and prevent the spindle from being raised, in which case the knee brake 3 would be dispensed with.

Having thus described my invention, what 95 I claim as new and desire to secure by Letters Patent is:—

1. The combination with a spindle supporting case or bolster, a spindle having a whirl thereon, a knee brake lever having a 100 central opening therethrough for the spindle bolster, and an opening for the knee brake lever post, and a downwardly extending engaging end, and a weighted end, and a leather washer supported on the upper surface of 105 said knee brake lever and surrounding the bolster, and adapted to engage the lower surface of said whirl, of a knee brake lever post extending loosely through said opening in 110 said knee brake lever, a hub loosely mounted on said post to rotate thereon, and having a friction finger thereon adapted to extend over the upper surface of said whirl, a screw 115 or bolt holding said hub on said post, an expansion spring extending within said hub and acting to hold said hub and finger in a raised position.

2. The combination with a spindle supporting case or bolster, a spindle having a whirl thereon, a knee brake lever having a 120 central opening therethrough for the spindle bolster, and an opening for the knee brake lever post, and a downwardly extending engaging end, and a weighted end, and a leather washer supported on the upper surface of 125 said knee brake lever and surrounding the bolster, and adapted to engage the lower surface of said whirl, of a knee brake lever post extending loosely through said opening in 130 said knee brake lever, a hub loosely mounted

on said post to rotate thereon, and having a friction finger thereon adapted to extend over the upper surface of said whirl, a screw or bolt holding said hub on said post, an expansion spring extending within said hub and acting to hold said hub and finger in a raised position, and said hub having its upper end recessed to receive the head of said screw or bolt, and provided with an engaging surface 10 to engage an engaging surface on said screw or bolt, to hold said hub and finger, and prevent rotary movement thereof.

3. The combination with a spindle supporting case or bolster, of a knee brake lever, having a central opening therethrough for the bolster, and an elongated opening therethrough for the passage of the friction finger, and said friction finger, having a hub loosely mounted on a stationary support, and 15 adapted to have a rotary movement, and be moved over the upper surface of said whirl,

and out of the path of said whirl, and a screw or bolt for holding the hub of said finger, an expansion spring encircling said screw or bolt within said hub, and the head of said screw or bolt engaging the upper surface of 25 said hub, to hold the finger in an operative or inoperative position.

4. The combination with a spindle supporting case, and a spindle having a whirl thereon, of a finger adapted to extend over said whirl and having a hub, a post on which said hub is loosely mounted, a screw for holding the hub and having a head with a flat surface to engage the upper end of the 30 hub, a spring acting to raise the hub and cause it to engage said screw head, to lock 35 said finger in operative position.
